UNITED STATES PATENT OFFICE.

JOSEF METZ, OF NEW YORK, N. Y.

RAIL-JOINT.

1,147,258.

Specification of Letters Patent. Patented July 20, 1915.

Application filed February 2, 1915. Serial No. 5,687.

To all whom it may concern:

Be it known that I, JOSEF METZ, a subject of the King of Hungary, residing at New York, in the county of New York and State of New York, have invented new and useful Improvements in Rail-Joints, of which the following is a specification.

This invention relates to a rail joint and has as its principal object to provide means whereby the smooth transit of the wheels 10 passing over said rail joints from one rail end to the other may be secured.

A further object of my invention is to provide a device of the character described, 15 which is simple in construction and comparatively cheap to manufacture, contrasting in this latter feature with the many known devices for obtaining the same result, which owing to their complicated nature necessitating much work on the rail ends, 20 are unpracticable from a commercial point of view.

I attain my objects by means of interlocking the rail ends in a simple and effective 25 fashion, preventing any respective vertical deviation thereof, and by means of cutting away the rail ends diagonally in respect to the longitudinal axis of the rails, whereby the wheels passing from one rail end to the 30 adjoining one will do so gradually and not strike suddenly against the edge of the rail end at the farther side of the space usually left between adjoining rails to allow for their expansion.

Reference will now be had to the accompanying drawing, in which:

Figure 1 is a side elevational view of a rail-joint constructed according to my invention, hidden parts being indicated by dotted lines; Fig. 2 is a plan view of the same; 40 Figs. 3 and 4 are side elevational views of the rail ends, one being the complement of the other.

Similar reference characters refer to similar parts throughout the several views.

Referring more particularly to the drawing, 5 and 6 are rail ends the adjoining faces

of which are cut away diagonally in respect to the longitudinal axis of the rails, as shown at 7 and 8, respectively. In the front edge 50 of the web of the rail end 5, at about mid-height, I provide a horizontal groove 9, open at the front, and on the front edge of the opposite rail-end 6 I provide a tongue 10 registering with the groove 9 and fitting 55 closely therein, so that when the two rail ends are secured together, it will prevent their vertical movement in respect to each other.

The front edge of the tongue 10 and the 60 rear wall of the groove 9 are also formed diagonally in a plane parallel with the front edges of the rails so that the rail ends can be cut out, immediately after passing the rolling mills, by one diagonal movement of a 65 shearing machine.

The rail ends constructed according to my invention may be joined together in any known way, such as by means of fish plates 11 and screw bolts 12. 70

The usual space between the meeting rail ends, to allow for the expansion of the rails, has to be provided also in the rail joint of my invention.

Having thus shown and described my invention, what I claim is:

In a rail joint, the ends of adjoining rails cut away diagonally in respect to their longitudinal axis, a horizontal groove formed in the front edge of the web of one rail end 80 and a tongue closely fitting into said groove formed on the front edge of the web of the other rail end, said groove adapted to engage said tongue and lock said rail ends from a respective vertical movement when 85 joined together, the front edge of said tongue and the rear wall of said groove being cut away diagonally in a plane parallel to the front ends of said rails, substantially as and for the purpose set forth.

JOSEF METZ.
